UNITED STATES PATENT OFFICE

159,053

TOY BOAT OR THE LIKE

Philip A. Derham, Rosemont, Pa., assignor to
Champion Plastics Corporation, New York,
N. Y., a corporation of New York

Application April 9, 1948, Serial No. 145,628

Term of patent 3½ years

(Cl. D34—15)

To all whom it may concern:

Be it known that Philip A. Derham, residing at Rosemont, the county of Montgomery, and State of Pennsylvania, whose business address is the same, has invented a new, original, and ornamental Design for Toy Boat or the like, of which the following is a specification, reference being had to the accompanying drawing, forming part thereof.

Figure 1 is a top plan view of a toy boat or the like, showing my new design;

Figure 2 is a side elevational view thereof;

Figure 3 is a front elevational view thereof; and

Figure 4 is a rear elevational view thereof.

I claim:

The ornamental design for a toy boat or the like, as shown.

PHILIP A. DERHAM.
